NECKTIE

Arthur N. Bachrach, New York, N. Y.

Application June 20, 1955, Serial No. 36,573

Term of patent 3½ years

(Cl. D3—16)

Fig. 1 is a view of necktie embodying the design in its untied condition with one end partly opened by turning back the top fold;

Fig. 2 is a view showing the necktie on somewhat smaller scale and in tied condition;

Fig. 3 is a sectional view on line 3—3 of Fig. 1.

The tie is symmetrical about the longitudinal central line of fold, the face of the folded tie opposite that shown in Fig. 1 being of similar appearance to the face shown.

I claim:

The ornamental design for a necktie, as shown and described.
